 graphie m. b. H., Berlin, Germany, a corpora-
 tion of Germany

Application January 23, 1940, Serial No. 315,161
 In Germany October 26, 1938

5 Claims. (Cl. 250—40)

Mechanism adapted to tune radio apparatus is known in the art in which the station names on the scale member are arranged, for instance, alphabetically rather than in the order of their 5 wave-lengths in order to facilitate the finding of a desired station. In one arrangement of this nature a stop pin serving for the setting is shifted along a slot posteriorly of which is journaled a shaft connected with the rotary condenser, metallic disks being seated upon the said shaft which are provided with cooperating stops or 10 detents. When the stop pin has been shifted as far as the desired station name, a separate knob serves to turn the rotary condenser until 15 it strikes.

The disadvantage of this known arrangement resides in difficult manipulation and operation seeing that two setting means must be used; furthermore, in the fact that a distinct stop disk 20 is required for each station to which the apparatus is to be tuned.

The present invention creates a simpler solution to the problem to provide an alphabetic scale in that the moving indicator member of the 25 station scale is in coupling relation and connection with two contact disks mounted upon a shaft, one of the said contact disks carrying a row or bank of contacts of which each one corresponds to the station to be tuned to in the sequence and 30 order of the station names on the scale, while the other contact disk has as many contacts in the sequence and disposition of the corresponding position of the tuning means, such as the rotary condenser of the receiver. Each contact mounted 35 on one disk in this scheme is conductively united with the corresponding contact (that is, the contact coordinated to the same sending station) of the respective other disk. Two contact brushes, one of which cooperates with the first contact 40 disk and is stationary while the other one cooperates with the second contact disk though being connected with the tuning means, are cut in a circuit which arrests a motor setting the tuning means as a conducting connection is established between the two brushes by way of the 45 contact disks.

Moreover, the scale bearing the station names in alphabetical order is movable and so designed that essentially only the name of the station just 50 tuned in will be visible behind a window formed in the wall of the box or panel. The scale more particularly is borne by a band or tape connected with the tuning means so that, even if the scale window is very reduced in size, the name of the 55 station tuned in will be easily legible even at a

greater distance. Scales of this kind have been known in the prior art, fundamentally speaking. But in the customary arrangement of the station names in the order of their frequencies, the search for the sending station using a scale of 5 this sort was very difficult and tedious so that it was recognized that an additional more easily readable scale was desirable.

An exemplified embodiment of the invention is shown schematically in the drawing. The knob 10 D, which slightly projects laterally of the casing or cabinet (not shown) of a receiver and which is to serve for tuning, is seated upon a shaft A₁ which supports two disks S₁ and S₂ made of insulation material. In the neighborhood of the 15 periphery, that is, a portion thereof comprising 180 degrees, there are disposed the contacts K₁ and K₂ which may be in the form of rivets and which extend between the opposite faces of the respective disks. The number of such contact 20 rivets to be mounted upon each disk is governed by the number of stations to be tuned. While the contact rivets are arranged at equal distances upon the disk S₁, they are spaced on disk S₂ in accordance with the positions of the rotary condenser C serving for the tuning when adjusted 25 to the various stations. The contact rivets K₁ are engaged by a stationary wiper brush K'₁, and the contact rivets K₂ are engaged by a contact brush K'₂ attached by means of an arm or 30 lever A to the shaft of the rotary condenser A₂. The shaft A₁ drives by way of the disks S₁ and S₂ a web or endless band B stretched out between two journaled rollers W₁ and W₂ on which the 35 station names (represented by the letters A, B, C,— to S) are arranged in alphabetical order. Of these names only a small part, that is, a part comprising one or a few station names is visible posteriorly of a window X shown dotted, fitted in the wall or panel of the receiver (not shown). 40

If a certain station name appears behind the window after adjustment of the rotary knob D, then brush K'₁ will engage a very definite contact rivet K₁ corresponding to the desired station, let us say K. To the same station corresponds a definite rotary or angular position of the shaft A₂ of the rotary condenser in which the brush K'₂ comes to be placed also opposite a very definite contact rivet K on the disk S₂. The contact rivets K₁ and K₂ coordinated to the same 50 sending station, which, of course, are staggered in respect to each other at will so as to suit the deviation between the alphabetical order and the wavelength sequence, are each united with each other by a lead of which only a few, L_L, L_H and L_O, 55

are represented in the drawing. In other words, each conductor or lead connects corresponding contacts on the disks S_1 and S_2 . For example, the conductor L_0 connects the contact O in disk S_1 with contact O on disk S_2 , etc.

Now, arrangements are so made that after setting to a certain station by the agency of the knob D , the tuning means shaft A_2 must trail until the brush K'_2 comes to be positioned opposite the coordinated contact rivet K_2 , in other words, until conducting connection has been established between the brushes K'_1 and K'_2 by way of the particular pair of contacts K_1 , K_2 corresponding to the desired station and the junction wire, say, L_H . This is accomplished by conductively connecting the two brushes by way of a slide ring K_3 , a brush contact K'_3 , a relay L and a source of potential supply Q . When energized the said relay L opens a normally closed contact T and thereby interrupts the circuit of a motor M , the shaft of which is connected through the intermediary of the friction wheels S_3 and S_4 or other suitable gearing with the shaft A_2 . In series relation to the switch T and the source of voltage supply Q' for the motor is a change-over or reversing switch U which is shifted by means of stops (not shown) on the rotary condenser so that by switching the potential from a clockwise winding to a winding causative of counter-clockwise rotation, or vice versa, the reversal of rotation of the setting means is insured.

Hence, the operation of the arrangement as hereinbefore described is as follows: When tuning in on a certain station by the aid of the rotary knob D the circuit which includes the relay winding L is first broken. The motor M is excited as the contact T is automatically closed, and it thus will turn the rotary condenser of the receiver until the desired position has been attained. When this happens, the brush K'_2 engages the contact rivet K_2 corresponding to the desired station and as a consequence closes, by way of a definite lead or conductor, such as L_0 , the corresponding contact O , and brush K'_1 , the circuit containing the relay L which breaks the motor circuit. A device which is provided for the purpose of insuring sharp, automatic tuning may serve to perfectly compensate such inaccuracy or lack of precision in the tuning as may still remain. Reproduction of sound is automatically stopped (silent tuning) while the tuning is proceeding by means of the relay L .

The two disks may be from 1 to 2 centimeters thick and they may have a diameter of 15 cm. The contact rivets may be fitted with soldering tags or lugs in order to facilitate the work of establishing the connections L_A —to L_S . In order to make it easier to establish the switch connections it is advisable to apply legends to the contact rivets on the disks with the corresponding call letters or wavelengths.

The contact rivets could also be spaced around the entire circumference of the disks if the arm A is not fitted directly on the rotary condenser shaft A_2 , but rather on a shaft connected therewith through a transmission gear whereby the range of rotation is enlarged to 360 degrees. The disks, if desired, could be replaced by drums or equivalent means.

Also the knob D is preferably not fitted directly on the shaft A_1 , but is connected therewith through reduction gearing in the usual way. The drive of the shaft A_1 could also be by motor if a second motor is provided therefor. A switch

mounted on the outside of the receiver apparatus serves to switch it in and reverse its rotation.

The potentials for energization of the relay L and of the motor M are preferably tapped from the power unit of the receiver so that no current will flow when the set is switched off.

The band B bearing the station names is suitably translucent, and the same is illuminated from the rear in the window behind which it becomes visible. The station names are arranged in large easily legible lettering upon the band, the names being alphabetical and equi-spaced. Of course, in exceptional cases the alphabetical order may be departed from. For instance, for reception of local stations it may be expedient to provide distinct spaces placed at the beginning of band B . Moreover, the band or ribbon could also be replaced by a disk or a drum. The use of a band, however, makes for particularly good utilization of space. Inasmuch as the conventional full-view scale may be dispensed with it is possible to design the whole front panel of the apparatus to act as a baffle for the loudspeaker.

What is claimed is:

1. Automatic tuning mechanism for a radio receiver provided with variable tuning means, comprising a motor for driving said tuning means, a pair of adjustable disks, each having a similar series of contacts, there being one contact in each series assigned to a predetermined station to be tuned in, a fixed contact brush cooperating with the contacts of one of the disks, a second contact brush adapted to be rotated in unison with the tuning means and cooperating with the contacts on the second disk, a conductor joining each pair of related contacts, one on each disk, a circuit including the contact brushes, any one of the conductors with their terminating contacts and a relay, said relay adapted when said circuit is completed to break the motor circuit, thereby arresting the tuning means at the position of adjustment for receiving the predetermined desired station.

2. Automatic tuning mechanism as defined in claim 1 wherein the contacts on the disk with which the fixed contact brush cooperates are arranged in a predetermined order, and the contacts on the second disk are arranged according to wavelength, each bearing a definite relation to an adjusted position of the tuning means for tuning in the predetermined station to which the contact is assigned.

3. Automatic tuning mechanism for a radio receiver provided with variable tuning means, comprising a motor for driving said tuning means, a pair of disks simultaneously adjustable step by step, each having an equal number of contacts, there being one contact on each disk assigned to a predetermined station to be tuned in, a fixed contact brush cooperating with the contacts of one of the disks, a second contact brush adapted to be rotated in unison with the tuning means and cooperating with the contacts on the second disk, a conductor joining each pair of contacts, one on each disk, which are assigned to a predetermined station, a circuit including the contact brushes, any one of the conductors depending upon the adjustment of the disks, the contacts associated with said conductor and a relay, said relay adapted when said circuit is completed to break the motor circuit, thereby arresting the tuning means at the position of adjustment for receiving the predetermined desired station.

4. Automatic tuning mechanism for a radio

receiver provided with variable tuning means, comprising a motor for driving said tuning means, a pair of manually adjustable disks, an indicator scale actuated by said disks and having the station designations appearing thereon in a predetermined sequence, each disk having a plurality of contacts equal in number to the predetermined stations desired to be automatically tuned in, one of said disks having its contacts arranged in the same sequence as the stations on the indicator scale, a fixed contact brush cooperating with said last mentioned disk, the second disk having its contacts arranged according to wavelength, a second contact brush movable in unison with the tuning means and cooperating with the contacts on the second disk, a conductor joining each pair of contacts one on each disk, which are assigned to a predetermined station, a circuit including the contact brushes, any one of the conductors depending upon the adjustment of the disks, the contacts associated with said conductor and a relay, said relay adapted when said circuit is completed to break the motor circuit, thereby arresting the tuning means at the position of adjustment for receiving the predetermined desired station.

5. Automatic tuning mechanism for a radio receiver provided with variable tuning means, comprising a motor for driving said tuning means, a pair of disks mounted on a common shaft, an indicator scale adapted to be moved in unison with said disks and having the station designations appearing thereon in alphabetical sequence, means for adjusting the disks and scale step by step to one of a predetermined number of stations, each disk having a series of contacts arranged adjacent its periphery, the number of such contacts on each disk being equal to the number of stations desired to be automatically tuned in, one of said disks having its contacts arranged in the same sequence as the stations on the indicator scale, a fixed contact brush cooperating with said last mentioned disk, the second disk having its contacts arranged according to wavelength, a second contact brush movable in unison with the tuning means and angularly adjustable to contact the contacts on the second disk, a conductor joining a corresponding pair of contacts, one on each disk, which are assigned to a predetermined station, a circuit including the contact brushes, any one of the conductors depending upon the adjustment of the disks and indicator scale, the contacts associated with said conductor and a relay, said relay adapted when said circuit is completed to break the motor circuit, thereby arresting the tuning means at the position of adjustment for receiving the desired station.
